US0D1061605S

(12) **United States Design Patent** (10) Patent No.: **US D1,061,605 S**
(45) Date of Patent: ** Feb. 11, 2025

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Jisu Son**, Suwon-si (KR); **Heyungjoo Kim**, Suwon-si (KR); **Heonwoo Lee**, Suwon-si (KR); **Jihyun Ahn**, Suwon-si (KR); **Miyeon Park**, Suwon-si (KR)

(73) Assignee: **Samsung Electronics Co., Ltd.**, Suwon-si (KR)

(**) Term: **15 Years**

(21) Appl. No.: **29/858,006**

(22) Filed: **Oct. 27, 2022**

(30) **Foreign Application Priority Data**

May 25, 2022 (KR) 30-2022-0020774

(51) LOC (15) Cl. **14-04**

(52) U.S. Cl.

USPC **D14/485**

(57) **CLAIM**

The ornamental design for a display screen or portion thereof with graphical user interface, as shown and described.

DESCRIPTION

FIG. 1 is a front view of a first embodiment of a display screen or portion thereof with graphical user interface, showing our new design;

FIG. 2 is a front view of a second embodiment of a display screen or portion thereof with graphical user interface, showing our new design;

FIG. 3 is a front view of a third embodiment of a display screen or portion thereof with graphical user interface, showing our new design; and,

FIG. 4 is a front view of a fourth embodiment of a display screen or portion thereof with graphical user interface, showing our new design.

The outer perimeter broken lines in the drawings represent a display screen or portion thereof and form no part of the claimed design. The remaining broken lines in the drawings depict portions of the graphical user interface which form no part of the claimed design.

1 Claim, 4 Drawing Sheets
